UNITED STATES PATENT OFFICE.

WALTER K. NORTHALL, OF NEW YORK, ASSIGNOR TO J. D. LINCOLN,
OF BROOKLYN, NEW YORK.

DESIGN FOR A CRUMB-BRUSH.

SPECIFICATION forming part of Design No. 17,015, dated December 7, 1886.

Application filed October 23, 1886. Serial No. 217,075. Term of patent 7 years.

To all whom it may concern:

Be it known that I, WALTER K. NORTHALL, a citizen of the United States, residing at New York, in the county and State of New York, 5 have invented and produced a new and original Design for Crumb-Brushes, of which the following is a specification, reference being had to the accompanying drawing, forming part thereof.

10 The drawing is a perspective view of my newly-designed brush.

The leading feature of my design consists in the angular shape or configuration of the brush A.

15 *a a* are two straight body portions of the brush, both lying in the same plane, and converging toward each other so as to form an acute angle at *b*.

B is the handle of the brush, projecting from one end of the body A and at an angle therewith. 20

C are the bristles, projecting from the under side of body A and at right angles thereto.

I claim—

The design for a crumb-brush herein shown 25 and described, the same consisting of a body, A, having its outer sides, *a a*, straight and converging to a point, *b*, forming an angular outline shape or configuration, and a handle, B, projecting from one end and at an angle 30 therewith.

WALTER K. NORTHALL.
